(No Model.)

E. G. GODDARD.

ROTARY MOLD BOARD PLOW.

No. 326,030.

Patented Sept. 8, 1885.

Attest:

A. Barthel
M. J. Mayne

Inventor:

Ezra G. Goddard
by his Atty Thos. J. Mayne

UNITED STATES PATENT OFFICE.

EZRA G. GODDARD, OF EAST SAGINAW, MICHIGAN.

ROTARY-MOLD-BOARD PLOW.

SPECIFICATION forming part of Letters Patent No. 326,030, dated September 8, 1885.

Application filed January 2, 1885. (No model.)

To all whom it may concern:

Be it known that I, EZRA G. GODDARD, of East Saginaw, in the county of Saginaw and State of Michigan, having invented new and useful Improvements in Rotary-Mold-Board Plows; and I do hereby declare that the following is a full, clear, and exact description thereof, reference being had to the accompanying drawings, which form a part of this specification.

This invention relates to certain new and novel improvements in the construction of plows.

The invention consists in the peculiar combinations and the construction and arrangement of parts, hereinafter more fully described and claimed.

Figure 1 is a perspective of my improved plow. Fig. 2 is a top plan, and Fig. 3 is a vertical cross-section through the axis of the disk.

In the accompanying drawings, which form a part of this specification, A represents the landside of my improved plow, which is provided with the plow-point B and share C, the heel of the share being connected to the landside by the brace D.

E represents the plow-beam, +shaped in cross-sections, the rear end of which is secured to the upper edge of the landside, while its forward end is provided with the ordinary clevis attachments. This beam is provided with a rearwardly-projecting arm, F, leaving a recess between said beam and arm; said recess extending beyond the longitudinal center of said beam, as shown in Figs. 1 and 2. In the end of said arm is suitably secured one end of a stationary shaft, G, upon which the rolling disk H is journaled, the opposite end of the shaft being secured to the main portion of the beam, so that said shaft is diagonal to the travel of the plow. I are the handles. This disk H may be either concave or flat upon its mold-board face, and is sufficiently large so that its periphery will form a continuation of the cutting edge of the share and point. It

will also be observed that a portion of the disk is hid behind the upper and inner edge of the share.

The disk is set at a suitable angle to the line of draft, so that in plowing the slice cut, incoming in contact with the disk, will compel the disk to rotate, and thereby very materially lessen the friction and lighten the draft. As the disk forms a continuation of the cutting-edge of the point and share, it will in its rotation cut the sod and free itself from material that would tend to clog beneath the beam.

While I have shown the beam as curved horizontally beyond the landside, it is evident that it may be arched vertically and have the disk rotate beneath it without departing from the spirit of my invention.

I am aware of the Patents Nos. 77,184 and 114,002, and make no claim to the constructions shown therein as forming part of my invention.

What I claim as my invention is—

1. In a plow, the beam E, provided with the rearwardly-projecting arm F, formed integral therewith, said beam and arm being constructed as shown, whereby a recess is left between the two, said recess extending forward beyond the longitudinal center of said beam, substantially as described.

2. In a plow, the beam E, +shaped in cross-section and provided with a bend, as shown, and with the rearwardly-projecting arm F, formed integral therewith, leaving a recess between said beam and arm, said recess extending forward beyond the longitudinal center of said beam, and said beam and arm enlarged to receive the shaft G, in combination with said shaft G, and the disk H, carried by said shaft and revolving in said recess, substantially as and for the purpose specified.

EZRA G. GODDARD.
